SNAP-ACTION SWITCH

Ralph B. Immel, Williamsville, N. Y., assignor to Westinghouse Electric Corporation, East Pittsburgh, Pa., a corporation of Pennsylvania

Application November 28, 1951, Serial No. 258,655

13 Claims. (Cl. 200—67)

My invention relates, generally, to electric switches and, more particularly, to switches of a type which operate with a snap action.

Relatively small control switches and limit switches are frequently required in systems for automatically controlling the operation of machinery. For such industrial applications, reliability and precision of operation at the same point in the travel of the switch-operating member are important features.

An object of my invention, generally stated, is to provide a snap-acting switch which is simple and reliable in operation and which may be economically manufactured.

A more specific object of my invention is to provide a snap-acting switch having a relatively small number of parts requiring close manufacturing tolerances.

Another object of my invention is to provide a snap-action switch having a relatively high current-carrying capacity.

A further object of my invention is to reduce friction between the moving parts of a snap-action switch.

Other objects of my invention will be explained fully hereinafter or will be apparent to those skilled in the art.

In accordance with one embodiment of my invention the bridging contact member of a snap-action switch is connected to a push-button operator by toggle levers which also function as spring members under stress to provide a force for holding the moving contacts against the stationary contacts, thereby insuring a relatively high contact pressure. When the push button is actuated, the spring members are stressed further until they go over-center, thereby operating the bridging contact member with a snap action.

For a better understanding of the nature and objects of the invention, reference may be had to the following detailed description, taken in conjunction with the accompanying drawing in which:

Figure 1 is a view, in side elevation, of a switch embodying the principal features of the invention, the switch casing cover being removed;

Fig. 2 is an enlarged and exploded view of certain parts of the switch, the parts being shown in perspective;

Fig. 3 is a view, in side elevation, of a modified form of switch, with part of the casing being broken away; and

Fig. 4 is a view, similar to Fig. 2, of parts of the switch shown in Fig. 3.

Referring to the drawing, and particularly to Figs. 1 and 2, the switch structure shown therein comprises a base 10, which may be molded from a suitable insulating material, and a cover (not shown) which may be attached to the base 10 by bolts or rivets inserted through openings 11 provided in the base 10. As shown, the base 10 has an opening 12 therein for a reciprocating operating member 13 for actuating the switch mechanism, as will be described more fully hereinafter.

2

Two pairs of oppositely disposed contact blocks 14 are mounted in the base 10. The contact blocks 14 may be composed of any suitable electrical conducting material. Each contact block has an integrally formed pin 15 which is inserted in a suitable opening provided in the base 10. As shown, the front corners of each block are cut away to provide shoulders 16 which are engaged by the cover of the casing to retain the contact blocks in position. A contact 17 is provided on each contact block 14. The contacts 17 are preferably composed of silver or a silver alloy. A threaded opening 18 is provided in the front end of each contact block for receiving a threaded screw 19 for making an electrical connection to the contact block.

A bridging contact member 21 is movably disposed between the upper pair of contact blocks 14 and the lower pair of contact blocks. As shown most clearly in Fig. 2, the bridging contact member 21 is generally rectangular in shape and has a generally rectangular opening 22 therein. The member 21 may be formed from a relatively thin sheet of conducting material, such as beryllium copper. The rigidity of the member 21 may be increased by providing downwardly turned flanges 23 at its outer edges and similar flanges 24 at the sides of the rectangular opening 22. In this manner, the contact member 21 may be relatively light in weight but at the same time relatively rigid. Thus, the contact member 21 has a low inertia and can be operated with a fast snap action. The bridging contact member 21 is provided with upper and lower contacts 25 at each end which are disposed to engage the contacts 17 on the contact blocks 14. The contacts 25 are preferably composed of the same material as the contacts 17.

As shown, the switch-operating member 13 is in the form of a push button, and it may be molded from a suitable insulating material. The top of the push button is rectangular in section, and the reciprocating movement of the push button is guided by the sides of the rectangular opening 12 in the base 10. A flange 26 is provided at the base of the push button to engage shoulders 27 on the base 10 to limit the upward movement of the push button 13. A guide pin 28 extends downwardly from the push button 13 into an opening 29 in the base 10, thereby also guiding the movement of the push button.

A coil spring 31 surrounds the guide pin 28 and both members extend through the opening 22 in the bridging contact member 21. The lower end of the spring 31 rests on shoulders 32 on the base 10, and the upper end of the spring 31 engages a clevis 33 which is also mounted on the guide pin 28. The clevis 33 has an opening 34 therein for receiving the guide pin 28. In this manner the spring 31 is compressed when the push button 13 is pressed downwardly, and it returns the push button 13 to its uppermost position when it is released.

As shown most clearly in Fig. 2, the clevis 33 has two downwardly extending spaced arms 35 each of which has a bearing notch 36 near its lower end. Two resilient spring toggle levers 37 are disposed between the arms 35 of the clevis 33 and the ends of the rectangular opening 22 in the bridging contact member 21. As shown most clearly in Fig. 2, each of the toggle members 37 is generally of a U shape and may be formed from a relatively thick piece of resilient spring material, such as spring steel.

One leg of the U-shaped member 37 has a flange 38 thereon having a notch 39 therein. The other leg has a notch 41 in each side edge of the leg. A notch 42 is provided in each end of the opening 22 in the bridging contact member 21. The switch mechanism may be as-

sembled by placing the notches 41 of the toggle members in the notches 42 in the bridging member 21 and placing the notches 36 in the clevis 33 in the notches 39 in the toggle members 37. Since the distance Z between the bearing notches 42 is less than the sum of the dimensions $X+2Y$, the spring toggle members 37 are stressed when assembled in the switch mechanism. As shown, the dimension X is the distance between the arms 35 of the clevis 33 at the bases of notches 36, and the dimension Y is the distance between the bearing notches 39 and 41 in the legs of each U-shaped toggle 37.

As shown in Fig. 1, the push button 13 is normally biased to its uppermost position by the spring 31 and the bridging contact member 21 is normally biased to its lowermost position by the spring toggle members 37 which, as previously explained, are stressed at all times when assembled in the switch mechanism. Thus, the contacts 25 on the bridging member 21 are held against the lower contacts 17 with sufficient contact pressure to enable the contact members to conduct relatively heavy currents.

When the push button 13 is depressed, the spring toggle levers 37 are stressed still further until the ends of the levers which are engaged by the arms 35 of the clevis 33 pass overcenter, thereby causing the bridging contact member 21 to be actuated upwardly with a fast snap action. The upward movement of the bridging contact member 21 is limited by the upper contacts 25 engaging the upper contacts 17. The spring toggle levers 37 are still under stress, thereby maintaining a good contact pressure between the upper contact members.

When the push button 13 is released, the return spring 31 returns it to the position shown in Fig. 1, thereby actuating the bridging contact member 21 downwardly by stressing the toggle members 37 until they pass overcenter. Thus, a snap action is obtained during operation of the bridging contact member 21 in either direction.

It will be observed that the knife-edge bearings 42 in the member 21 are sufficiently far apart to overcome any tendency of the member 21 to rotate about the guide pin 28 as a center, thereby reducing friction between the moving parts of the switch mechanism. Furthermore, the parts of the switch mechanism are relatively simple in structure and require that only the X, Y, and Z dimensions be maintained with relatively close tolerances during the manufacture of the parts.

The switch shown in Figs. 3 and 4 is somewhat similar in structure to the one shown in Figs. 1 and 2. A base 50, which may be molded from a suitable insulating material, has openings 51 therein for attaching a cover (not shown) to the base. A rectangular opening 52 is provided in the base for receiving a push button 53. Contact terminals 54 are so mounted in the base as to be accessible from the bottom of the switch instead of from the side as in the switch shown in Fig. 1. As shown, each outer terminal 54 has a U-shaped bracket 55 attached thereto. The bracket 55 carries a contact 56. Each inner terminal 54 has a bracket 57 attached thereto which supports a contact 58 disposed below a corresponding contact 56. Terminal screws 59 are provided in the terminals 54 for making electrical connections to the terminals.

A generally rectangular bridging contact member 61 has a generally rectangular opening 62 therein. The member 61 is preferably composed of the same material as the member 21, and it may be provided with flanges 63 at its outer edges to increase its rigidity. Upper and lower contacts 65 are attached near the ends of the bridging member 61. The contacts 65 are preferably composed of silver or a silver alloy as are the contacts 56 and 58.

As shown, the push button 53 is rectangular in shape and has a flange 66 at its base. The flange 66 engages shoulders 67 in the base 50 to limit the upward movement of the push button. A guide pin 68 extends downwardly from the push button. An opening 69 is provided in the base 50 for the lower end of the guide pin 68. Thus, the

reciprocating movement of the push button is guided by the sides of the openings 52 and 69 provided in the base 50.

5 A coil spring 71 surrounds the guide pin 68 with the lower end of the spring resting on shoulders 72 in the base 50. The upper end of the spring 71 engages a connecting bar 73 which connects the inner legs of generally U-shaped spring toggle members 74. A guide plate 75 having downwardly extending flanges 76 may be disposed between the connecting bar 73 and the push button 53. The push button 53 may be provided with a groove 77 for receiving the guide plate 75. The guide plate 75 has an opening 78 therein, and the bar 73 has an opening 79 therein through which the guide pin 68 extends.

As shown most clearly in Fig. 4, the U-shaped spring toggle members 74 are formed integrally with the connecting bar 73. Bearing notches 81 are provided in the outer legs of the U-shaped members 74. A bearing notch 82 is provided in each end of the opening 62 in the bridging contact member 61. The toggle members are assembled with the bearing notches 81 placed in the notches 82. Since the dimension Y, which is the distance between the outer ends of the U-shaped toggle members, is greater than the dimension Z, which is the distance between the ends of the opening 62, the toggle members are stressed at all times when assembled in the switch. Thus, they function in the same manner as the toggle members 37 to maintain contact pressure between the contact members of the switch.

The guide plate 75 holds the moving assembly in alignment with the stationary contacts. Small pivot surfaces or ridges 83 are provided on the underside of the guide plate 75 to permit the moving contact assembly to align itself with the stationary contacts. If desired, the guide plate 75 may be omitted and the push button 53 permitted to rest directly on the bar 73 with the bar 73 disposed in the groove 77. The ridges 83 could be molded on the underside of the push button 53.

The operation of the switch shown in Figs. 3 and 4 is similar to the one shown in Figs. 1 and 2. When the push button 53 is depressed, the stress on the spring toggle members 74 is increased until the connecting bar 73 passes overcenter, thereby causing the bridging contact member 61 to be moved upwardly with a snap action. The upward movement of the bridging member is limited by the upper contacts 65 engaging the contacts 56. The spring toggle members 74 are still stressed to maintain a relatively high contact pressure between the contacts 56 and 65. When the push button 53 is released, the return spring 71 actuates the push button to its uppermost position, thereby causing the spring toggle members 74 to return the bridging contact member 61 to its lowermost position.

The switch shown in Figs. 3 and 4 is relatively simple in structure. Most of the metal parts may be stamped from sheet metal, and the insulating parts may be molded. The only dimensions which must be maintained with relatively close manufacturing tolerances are the dimensions Y and Z. Furthermore, the parts may be easily assembled in the switch casing.

From the foregoing description, it is apparent that I have provided switch structures which are simple in construction and economical to manufacture and assemble. The moving contact members are actuated with a snap action at substantially the same point in the travel of the operating member. Relatively high contact pressure is obtained by maintaining the spring members of the switch under stress at all times, and the simplicity of structure is obtained by utilizing toggle-connecting levers which also function as the spring members for obtaining the snap action and/or maintaining the contact pressure. The switch may be operated manually, or it may be utilized in the automatic control of machinery and operated by parts of the machines being controlled.

Since numerous changes may be made in the above-

described construction and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In an electric switch, in combination, oppositely disposed pairs of spaced stationary contacts, a bridging contact member movable into and out of bridging engagement with said stationary contacts, a reciprocating operating member, a pair of generally U-shaped spring toggle members pivotally connected to the bridging contact member and joined together by a connecting bar, said bar connecting the operating member to the toggle members to actuate the bridging contact member between the oppositely disposed contacts, said spring toggle members being stressed when assembled in the switch to bias the bridging contact member against one pair of stationary contacts.

2. In an electric switch, in combination, oppositely disposed pairs of spaced stationary contacts, a bridging contact member movable into and out of bridging engagement with said stationary contacts, a reciprocating operating member, and a one-piece spring member having integrally formed generally U-shaped toggle arms pivotally connected to the bridging contact member and operatively connected to the operating member to actuate the bridging contact member between the oppositely disposed contacts.

3. In an electric switch, in combination, oppositely disposed pairs of spaced stationary contacts, a bridging contact member movable into and out of bridging engagement with said stationary contacts, a reciprocating operating member, and a one-piece spring member having integrally formed generally U-shaped toggle arms pivotally connected to the bridging contact member and operatively connected to the operating member to actuate the bridging contact member between the oppositely disposed contacts, said spring toggle arms being stressed when assembled in the switch to bias the bridging contact member against one pair of stationary contacts.

4. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, and separately mounted spring toggle members connecting the operating member and the ends of the rectangular opening in the bridging contact member, portions of said toggle members being disposed at one side of the bridging contact member to pass through the opening in the bridging contact member from one side of the bridging contact member to the other during actuation of the bridging contact member by reciprocation of the operating member.

5. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, separately mounted spring toggle members connecting the operating member

and the ends of the rectangular opening in the bridging contact member, portions of said toggle members being disposed at one side of the bridging contact member to pass through the opening in the bridging contact member from one side of the bridging contact member to the other during actuation of the bridging contact member by reciprocation of the operating member, said operating member being movable in one direction by an external force, and a return spring for moving the operating member in the opposite direction.

6. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, separately mounted spring toggle members connecting the operating member and the ends of the rectangular opening in the bridging contact member, portions of said toggle members being disposed at one side of the bridging contact member to pass through the opening in the bridging contact member from one side of the bridging contact member to the other during actuation of the bridging contact member by reciprocation of the operating member, said operating member being movable in one direction by an external force, and a return spring for moving the operating member in the opposite direction, said return spring surrounding said guide pin.

7. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, separately mounted spring toggle members connecting the operating member and the ends of the rectangular opening in the bridging contact member, portions of said toggle members being disposed at one side of the bridging contact member to pass through the opening in the bridging contact member from one side of the bridging contact member to the other during actuation of the bridging contact member by reciprocation of the operating member, said operating member being movable in one direction by an external force, and a return spring for moving the operating member in the opposite direction, said return spring surrounding said guide pin and extending through the opening in the bridging contact member.

8. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, separately mounted spring toggle members connecting the operating member and the ends of the rectangular opening in the bridging contact member, portions of said toggle members being disposed at one side of the bridging contact member to pass through

the opening in the bridging contact member from one side of the bridging contact member to the other during actuation of the bridging contact member by reciprocation of the operating member, said operating member being movable in one direction by an external force, and a return spring for moving the operating member in the opposite direction, said return spring surrounding said guide pin and having one end engaging said base below the bridging contact member and the other end engaging the operating member above the bridging contact member.

9. An electric switch comprising a base having a generally rectangular recess therein, generally oblong contact blocks disposed at the corners of said recess, a contact member on one side of each contact block, a terminal screw threaded into the end of each block, a substantially rigid bridging contact member movable into and out of bridging engagement with oppositely disposed pairs of said contact members, said bridging contact member having a generally rectangular opening therein, a reciprocating operating member slidably disposed at one side of the recess and having a guide pin slidably disposed at the opposite side of the recess, toggle levers engaging the ends of the rectangular opening in the bridging contact member, and spring arms connecting the toggle levers and the operating member, portions of said toggle levers being disposed at one side of the bridging contact member to pass through the opening in the bridging contact member from one side of the bridging contact member to the other during actuation of the bridging contact member by reciprocation of the operating member.

10. An electric switch comprising a base having a recess therein, spaced stationary contacts disposed in said recess, a substantially rigid bridging contact member movable into and out of bridging engagement with said stationary contacts, said bridging contact member having a generally rectangular opening therein, a reciprocating operating member slidably disposed at one side of the recess, a guide pin for the operating member engaging the opposite side of said recess, and spring toggle members connecting the ends of the rectangular opening in the bridging contact member and the operating member, portions of said toggle members being disposed at one side of the bridging contact member to pass through the opening in the bridging contact member from one side of the bridging contact member to the other during actuation of the bridging contact member by reciprocation of the operating member.

11. An electric switch comprising a base having a recess therein, spaced stationary contacts disposed in said recess, a substantially rigid bridging contact member movable into and out of bridging engagement with said stationary contacts, said bridging contact member having a generally rectangular opening therein, a reciprocating operating member slidably disposed at one side of the recess, a guide pin for the operating member disposed in said recess, spring toggle members connecting the ends of the rectangular opening in the bridging contact member and the operating member, portions of said toggle members being disposed at one side of the bridging contact member to pass through the opening in the bridging contact member from one side of the bridging contact member to the other during actuation of the bridging contact member by reciprocation of the operating member.

5 contact member by reciprocation of the operating member, said operating member being movable in one direction by an external force, and a return spring for moving the operating member in the opposite direction, said return spring surrounding said guide pin.

12. An electric switch comprising a base having a recess therein, spaced stationary contacts disposed in said recess, a substantially rigid bridging contact member movable into and out of bridging engagement with said stationary contacts, said bridging contact member having a generally rectangular opening therein, a reciprocating operating member slidably disposed at one side of the recess, a guide pin for the operating member engaging the opposite side of said recess, a spring-seating member movable with said operating member, said spring-seating member having an opening therein for said guide pin and oppositely disposed spring seats thereon, and spring toggle members connecting the ends of the rectangular opening in the bridging contact member and the spring seats on said spring-seating member, portions of said toggle members being disposed at one side of the bridging contact member to pass through the opening in the bridging contact member from one side of the bridging contact member to the other during actuation of the bridging contact member by reciprocation of the operating member.

20 13. An electric switch comprising a base having a recess therein, spaced stationary contacts disposed in said recess, a substantially rigid bridging contact member movable into and out of bridging engagement with said stationary contacts, said bridging contact member having a generally rectangular opening therein, a reciprocating operating member slidably disposed at one side of the recess, a guide pin for the operating member disposed in said recess, a spring-seating member movable with said operating member, said spring-seating member having an opening therein for said guide pin and oppositely disposed spring seats thereon, spring toggle members connecting the ends of the rectangular opening in the bridging contact member and the spring seats on said spring-seating member, portions of said toggle members being disposed at one side of the bridging contact member to pass through the opening in the bridging contact member from one side of the bridging contact member to the other during actuation of the bridging contact member by reciprocation of the operating member.

25 30 35 40 45 50

14. An electric switch comprising a base having a recess therein, spaced stationary contacts disposed in said recess, a substantially rigid bridging contact member movable into and out of bridging engagement with said stationary contacts, said bridging contact member having a generally rectangular opening therein, a reciprocating operating member slidably disposed at one side of the recess, a guide pin for the operating member disposed in said recess, a spring-seating member movable with said operating member, said spring-seating member having an opening therein for said guide pin and oppositely disposed spring seats thereon, spring toggle members connecting the ends of the rectangular opening in the bridging contact member and the spring seats on said spring-seating member, portions of said toggle members being disposed at one side of the bridging contact member to pass through the opening in the bridging contact member from one side of the bridging contact member to the other during actuation of the bridging contact member by reciprocation of the operating member, said operating member being movable in one direction by an external force, and a return spring for moving the operating member in the opposite direction, said return spring surrounding said guide pin.
